UNITED STATES PATENT OFFICE.

CHARLES E. SHADALL, OF MILWAUKEE, WISCONSIN, ASSIGNOR, BY DIRECT AND MESNE ASSIGNMENTS, TO SHADALL MANUFACTURING COMPANY, OF WAUWATOSA, WISCONSIN, A CORPORATION OF WISCONSIN.

VENTILATING APPARATUS.

1,216,247.

Specification of Letters Patent. Patented Feb. 13, 1917.

Application filed July 5, 1912. Serial No. 707,657.

To all whom it may concern:

Be it known that I, CHARLES E. SHADALL, a citizen of the United States, residing at Milwaukee, in the county of Milwaukee and 5 State of Wisconsin, have invented certain new and useful Improvements in Ventilating Apparatus, of which the following is a specification, reference being had to the accompanying drawing, forming a part 10 thereof.

This invention relates more particularly to ventilating apparatus of the class shown and described in United States Letters Patent No. 1,004,917, issued to me October 15 3, 1911, for removing from water closet fixtures such as bowls and urinals, foul air and odors, and preventing the same from escaping into the rooms in which such fixtures are located.

Its main objects are to automatically shift 20 the spreader or deflector of the aspirator into working position by the pressure, weight or buoyant effect of the water admitted to the aspirator for producing a current of air therein; to make the spreader self-centering with respect to the jet orifice in which it works; to admit of locating the aspirator at any distance from the fixture with which it is connected or in an inacces- 25 sible place; and generally to improve the construction and operation of apparatus of this class.

It consists in the construction, arrangement and combination of parts as herein- 30 after particularly described and pointed out in the claims.

In the accompanying drawing like characters designate the same parts in the several figures.

Figure 1 is a view partly in side elevation and partly in vertical section of ventilating apparatus embodying the invention as applied to a water closet; Fig. 2 is a similar view showing a modification; Fig. 3 is a similar view of another modification; and Fig. 4 is a vertical section of still another modification of the aspirator.

Referring to Fig. 1, *a* designates an ordinary closet bowl having the usual trapped discharge passage *b* in the lower part thereof and an annular flushing channel *c* surrounding the upper part of the bowl and opening on the under side into the same. An elevated flushing tank *d* is connected with the

channel *c* in the bowl by a pipe *e*, in the usual manner.

The bowl is provided with a hinged seat *f*, which is normally held partially open or elevated by a spring or springs *g*.

A water supply pipe *h* leads into the tank *d*.

An aspirator casing *i* is formed or provided with a mixing and air entraining tube or passage *j* opening at the ends into inlet and outlet compartments. An air inlet or suction pipe *k* connects the inlet compartment of the casing with the bowl. In the present instance it is shown as connected indirectly with the channel *c* in the bowl through the lower portion of the flushing pipe *e*. An air outlet or escape pipe *l* connects with the outlet compartment of the casing in communication with the opposite end of the mixing tube or passage *j* and leads outside of the building in which the fixture is located, or into a ventilating flue with which the building may be provided.

A water chamber *m* located in the upper part of the aspirator casing, has a jet orifice *n* in the bottom or lower wall thereof, and in axial alignment with the mixing tube or passage *j*. The top or upper wall of the chamber *m* is formed with an opening *o* and an internal valve seat surrounding said opening.

A float basin or receptacle *p* is mounted on the chamber *m* and communicates therewith through the opening *o*. The basin or receptacle *p* is provided with a float *q*, connected by a depending stem *r* with an upwardly closing valve *s*, which fits the seat around the opening *o*. The valve *s* is normally supported in its open position by the float *q* resting upon an upwardly projecting rim of the chamber *m* around the opening *o*, and is guided and held in the chamber *m* by wings or other means, in proper relation to the jet orifice *n* and to the valve seat and opening *o*.

A spreader *t*, pivotally connected by a ball and socket or other universal joint, with the valve *s*, extends downwardly therefrom through the jet orifice *n* and is formed or provided at its lower end with an enlarged conical head which by reason of its loose universal joint connection with the valve, is made self-centering with relation to the jet orifice when water is admitted to the

chamber m , and the head of the spreader is thereby shifted upwardly into working position in said orifice, the action of the water passing through the orifice operating 5 to hold the spreader centrally therein so as to produce a symmetrical hollow conical jet, the most effective for entraining the maximum volume of air with a minimum amount of water.

10 The float basin or receptacle and the float are inclosed by a casing or housing u , which opens at the bottom around the chamber m into the upper part of the aspirator casing, so that any overflow of water from said 15 basin or receptacle will be discharged into the aspirator casing and conducted therefrom through the drain pipe v leading from the lower part thereof, and in the present case, into the bowl a between the seat f and 20 the top of the bowl. This pipe v serves, as shown, in connection with the pipes e and h , for removing foul air and odors as well as for the discharge of water from the aspirator, and if made of sufficient size, it may 25 serve alone for the air inlet to the aspirator, and the pipe h may be dispensed with.

In order to maintain an air draft through the pipe v and to avoid weakening the draft through the pipe h when the two pipes are 30 used, as shown, or when the pipe v is used alone as the common air inlet and water discharge connection, a water seal is provided in the lower part of the aspirator casing between the inlet and outlet 35 compartments. This is made by extending a transverse wall w upwardly from the bottom of the casing adjacent to the opening into the pipe v and another wall x , downwardly from the adjacent side of the mixing 40 tube or passage j , the bottom of the casing being preferably inclined downward toward the opening into the pipe v as shown, and the upwardly projecting wall w forming a pocket or trap into which the 45 downwardly extending wall x projects. The wall w is preferably formed next to the inclined bottom of the casing with a restricted drain opening y , which allows the 50 water to gradually escape from the seal or pocket into the pipe v when the supply to the aspirator is cut off, and thus prevent freezing in cold weather. These walls w and x being spaced apart, as shown, while providing for an effective water seal which 55 prevents the air from escaping through the outlet pipe l without first passing through the mixing tube or passage j , permits the free discharge of water from the lower part of the casing into the pipe v when the aspirator is in operation. A pipe z connects the 60 chamber m with the pipe h or other convenient source of water supply. This pipe is provided adjacent to the closet bowl or other fixture, with a starting valve 2, for 65 controlling the supply of water to the aspirator.

An easily operated self-closing valve of the kind shown in the drawing, is preferably used for this purpose.

The valve case is formed with two chambers, an inlet chamber and an outlet chamber connected by a port normally closed by a valve disk 3 held to its seat by a spring 4. The stem 5 of the valve, which opens against the water pressure, projects into the outlet chamber in position to be engaged by 70 a cross head 6, on a rod 7, which has a sliding bearing in the valve case parallel with the valve stem and passes through a cavity 8, formed in the case and connected by a drain pipe 9 with the flush pipe e , or any 75 convenient part of the apparatus into which any leakage of water around said rod may be discharged. The rod 7 may be provided adjacent to the bowl a or other fixture, with a head or handle 10 operated by hand, or it 80 may be connected by a lever 11 with a thrust rod 12, engaging an arm 13 on the seat f , so that the valve will be automatically 85 opened when the seat is depressed.

The aspirator and the valve controlling 90 the supply of water thereto, are shown as located behind the wall of the room in which the bowl or other fixture to be ventilated is placed, so as to be out of the way and hidden from view. They may be located at any 95 distance from the fixture above or below it, as for example, in an attic or cellar, the pipe connections being extended and arranged accordingly.

As shown by Fig. 1, the float casing or 100 housing u , is provided with a removable cover and is removably mounted with the chamber m on the upper open end of the aspirator casing i so as to provide easy 105 access to internal parts of the apparatus for inspection and repairs. The casing of the controlling valve 2 is also provided with removable heads or covers to afford access to internal parts and to provide for assembling the same.

In the operation of the apparatus, when the fixture is in use, the valve 2 is opened either by hand or automatically by the depression of the seat f , thereby admitting 110 water through the pipe z into the chamber m . The jet orifice n around the stem of the spreader t being of smaller area than the bore of the supply pipe z , the water immediately fills the chamber m , overflowing through the opening o into the float basin or receptacle p and lifting the float q , which in turn lifts and closes the valve s and at the same time moves the head of the spreader upward into working position in 115 said orifice, further restricting its area. The pressure of the water on the under side of the valve s , holds the same closed, and a thin conical jet issuing from the orifice around the spreader into the mixing tube or passage j , entrains air from the upper 120

125 130 controlling the supply of water to the aspirator.

compartment of the casing *i* and forces it out of the lower compartment of the casing into the escape pipe *l*. Foul air, with any offensive odors, is drawn from the bowl *a* 5 through the pipes *e* and *k*, into the aspirator and prevented from escaping into the room in which the bowl is located.

The water discharged through the jet orifice *n* and passing through the mixing tube 10 or passage *j* into the lower part of the aspirator casing, first fills the pocket formed by the wall *w* with the inclined bottom of the casing and forms a seal with the depending wall *x*. It then overflows the upper edge 15 of the wall *w* and escapes through the pipe *v* into the bowl. Air is also drawn from the upper part of the bowl through the pipe *v*, and passing upwardly in the casing *i* along one side of the mixing tube or passage 20 *j*, is forced by the water jet with air entering the aspirator from pipe *k*, through said mixing tube or passage and discharged through the pipe *l*.

When the seat *f* or handle 10 is released, 25 the valve *3* is closed by the spring *4*, thereby shutting off the supply of water from the chamber *m*. The float *q* then descends, permitting the valve *s* to open by gravity and permitting the spreader *t* to move downward 30 into the position in which it is shown by the drawing, thereby increasing the area of the jet opening *n*, permitting an increased flow of the water remaining in said chamber through said opening. The spreader 35 and the opposing walls of the jet opening are thus thoroughly flushed, and any sediment or dirt adhering thereto is removed, so that the apparatus is kept in working order without care or attention so far as 40 the production of a water jet is concerned.

When the flow of water from the chamber *m* ceases, the water confined by the wall *w* gradually escapes through the opening *y* 45 into the pipe *v*, so that injury to the aspirator by the freezing of water therein, is avoided.

Referring to Fig. 2, showing a modification of the apparatus, the lower part of the aspirator casing *i'* is connected with the bowl *a*, which is formed with an extra or 50 special opening for the purpose, by a pipe *k'* which serves both as a suction and air inlet and as a water outlet for the aspirator, taking the place of the pipes *k* and *v* of Fig. 1.

55 The aspirator casing is formed or provided at the top with an extension or chamber *u'* which extends into the same above and in line with the mixing tube or passage *j*.

60 An expandible water chamber *m'* takes the place of the chamber *m* of Fig. 1. The chamber *m'* is formed of annularly corrugated flexible sheet metal or the like, so that 65 it is expandible and contractible axially. It is attached at its upper end to the top or

removable cover of the extension or chamber *u'*, and in its lower movable head is formed with the jet orifice *n*. The spreader *t* is pivotally connected at its upper end with the stationary top or cover of the extension or chamber *u'*, and the water supply pipe *z* is connected centrally with said cover in communication with the interior of the expandible chamber *m'*. The transverse hole through the upper end of the spreader stem 70 through which the pivot pin passes, is enlarged from the center toward the ends, as shown in Fig. 4, so that the conical head at the lower end of the spreader is capable of lateral movement in all directions and thus 75 becomes self-centering with respect to the orifice *n*.

In the operation of the device, when the controlling valve *2* is opened and water admitted to the expandible chamber *m'*, said 80 chamber is filled and subjected to pressure owing to the restricted area of the jet orifice *n*. As a consequence, the lower head of the chamber is moved downward against the bottom of the extension or chamber *u'*, which 85 serves as a stop therefor, and the jet orifice *n* is brought into working position relative to the conical head of the spreader. When the valve *2* is closed and the water supply 90 cut off from the aspirator, the chamber *m'* being relieved of internal pressure, contracts by reason of the resiliency of its corrugated or fluted wall, and moves the jet orifice *n* 95 upward into its normal position, away from the head of the spreader, thereby permitting 100 an increased flow of water, which flushes the opposing walls of the orifice and spreader, dislodging and removing any dirt or obstruction which might otherwise accumulate and interfere with the operation of 105 the apparatus.

In other respects the construction and operation of the apparatus as shown in Fig. 2, is substantially the same as of the apparatus 110 shown in Fig. 1.

Referring to Fig. 3, showing a further modification of the apparatus, the aspirator chamber *i''* is formed with upper and lower compartments which have no communication with each other except through the mixing tube or passage *j*. The upper compartment is provided with a water chamber *m''*, which may be formed as shown, with the detachable cover of the casing. In the lower head or bottom of this chamber, which is 115 made removable, the jet orifice *n* is formed in axial alinement with the tube or passage *j*. The spreader *t* is connected at its upper end by a ball and socket or universal joint with a piston *q'* fitted in the upper part of said 120 chamber above the connection of the water supply pipe *z* therewith. An air vent opening 14, connects the upper end of the chamber with the upper compartment of the aspirator casing. The piston *q'* is provided 125

130

with a stop 15 for limiting its downward movement. The water discharge pipe v' leading from the bottom of the lower compartment of the aspirator casing in this case 5 discharges into the flushing tank d instead of into the closet bowl, as in the forms of apparatus shown in the two preceding figures.

In the operation of the apparatus shown 10 by Fig. 3, when the valve 2 is opened and water is admitted to the chamber m'' , the piston q' is lifted, carrying the head of the spreader t upward into working position relative to the jet orifice n . When the valve 15 2 is closed and water is cut off from the aspirator, the piston q' with the spreader t descends by gravity to its original position, in which it is arrested by the stop 15. In other respects the construction and operation 20 of this form of the apparatus are substantially like those of the forms shown in Figs. 1 and 2.

Referring to Fig. 4, showing a further modification of the aspirator, the casing i''' 25 is substantially like that shown in Fig. 1, except that in place of the float, float basin or receptacle and housing, it is extended farther upward and provided with a removable cover, and inside above the mixing 30 tube or passage j , with a water chamber m''' . The top or upper head of this chamber, which is removable, is formed with an opening o' , and on the under side with a seat for the normally open and upwardly closing 35 valve s . The spreader t , which passes through the jet orifice n in the bottom wall or head of said chamber in axial alinement with the tube or passage j , is pivotally connected at its upper end with the valve s , 40 which in turn has an upwardly projecting stem passing through the opening o' and connected with a disk q'' , which normally rests on the upper head or cover of the chamber m''' over said opening. The valve 45 s and the moving parts connected therewith are held in place with relation to the orifice n and opening o' by guides 16 on the cover.

When water is admitted to this form of the aspirator, after filling the chamber m''' , 50 it passes upwardly through the opening o' , lifting the disk q'' and with it the valve s and spreader t . The valve being closed, stops the flow of water through the opening o' and is held against its seat by the internal 55 pressure in chamber m''' as long as water is admitted thereto. When the supply of water to the aspirator is cut off, the valve s with the disk q'' and the spreader t descends by gravity to its original position, as shown by 60 the drawing. In other respects the construction and operation of this form of the aspirator are substantially the same as those of the forms shown in the other figures.

Various changes in the details of construction and arrangement of parts other 65

than those herein specifically shown and described may be made, without materially affecting the principle and mode of operation of the apparatus and without departure from the spirit and scope of the invention. 70

I claim:

1. In ventilating apparatus the combination of a water chamber having a jet orifice in the lower part and an opening and valve seat in the upper part, a float receptacle 75 above and communicating with said chamber through said opening, an upwardly closing valve fitted to said seat, a float in said receptacle connected with said valve, a spreader connected with said valve and extending axially downward therefrom into said jet orifice, and a valve controlled water supply connection with said chamber.

2. In ventilating apparatus the combination of a water chamber having a jet orifice 80 in the lower part and an opening and valve seat in the upper part thereof, a float receptacle located above said chamber and communicating therewith through said opening, a normally open and upwardly closing valve 85 fitting said seat, a float in said receptacle connected through said opening with the valve, a spreader pivotally connected with said valve and extending downwardly therefrom into the jet orifice in which it is self-centering, and a valve controlled water supply connection with said chamber. 95

3. In ventilating apparatus the combination of an aspirator casing having a mixing tube or passage, air inlet and outlet connections communicating with opposite ends of 100 said tube or passage and a separate water discharge connection below said air connections, a water chamber having a jet orifice in alinement with the mixing tube and a 105 spreader, one of which is movable axially relative to the other into working position of restricted flow by water admitted to said chamber and returns automatically to its normal position of unrestricted flow, and a 110 valve controlled water supply connection with said chamber.

4. In ventilating apparatus the combination of an aspirator casing having an air entraining passage, air inlet and outlet connections communicating with opposite ends of 115 said passage, and a separate water discharge connection below said air connections; a water chamber having a jet orifice in alinement with said air entraining passage and a self-centering spreader one of 120 which is axially movable relative to the other into its working position of restricted flow by water admitted to said chamber, and is automatically returnable to its normal position of unrestricted flow; and a valve controlled water supply connection with said chamber. 125

5. In ventilating apparatus the combination of an aspirator casing provided with a 130

- mixing tube or passage and having an air outlet connection and a common air inlet and water outlet connection communicating with opposite ends of said mixing tube, and
5 a water sealed outlet between the air inlet and the air outlet compartments of the casing, a water chamber having a jet orifice in alinement with said mixing tube, and a spreader, one of which is movable axially relative to the other into working position by water admitted to said chamber, and a valve controlled water supply connection with said chamber.
10 6. In ventilating apparatus, a casing having an air entraining passage, an air inlet, an air outlet, a water jet directed lengthwise of said passage toward said outlet, and a water sealed discharge connection opening from said casing below said air outlet.
20 7. In ventilating apparatus, a casing having an air entraining passage, an air inlet, an air outlet connection and a common air inlet and water outlet connection communicating with opposite ends of said mixing tube, and a water sealed outlet between the air inlet and the air outlet compartments of the casing, a water chamber having a jet orifice in alinement with said mixing tube, and a spreader, one of which is movable axially relative to the other into working position by water admitted to said chamber, and a valve controlled water supply connection with said chamber.
8. In ventilating apparatus the combination of an air entraining passage having an air inlet and an outlet, a jet orifice directed lengthwise of said passage toward its outlet, a liquid supply connection communicating with said orifice, and a movably mounted spreader extending into said orifice and adapted to be centered therein by the flow of liquid therethrough.
- 30 35

In witness whereof I hereto affix my signature in presence of two witnesses.
